Jack Meltzer, Los Angeles, Calif.

Application October 24, 1951, Serial No. 252,905

1 Claim. (Cl. 12—142)

1

My present invention relates generally to shoes, and has particular reference to articles of foot-wear in which a sock lining or its equivalent is secured along its entire periphery to the lower edge of an upper.

Shoes and slippers of the so-called "slip-lasted" variety are illustrative of the footwear for which my invention is intended, but certain features of the invention are also applicable to other types of footwear, such as "soft sole" slippers, moccasins, etc.

A more particular object of the invention lies in the provision of an improved procedure to be employed in manufacturing footwear of the character referred to, whereby the advantages of a stiff premolded heel counter are attained in a shoe having a sock lining, or its equivalent, secured throughout its peripheral extent to the lower edge of the upper. As is known, a sock lining which is stitched in all around the shoe periphery is highly desirable because it is not susceptible to displacement and is devoid of edges which may curl and cause discomfort or which may impair the attractiveness of shoes having openings at the toe or elsewhere. Moccasins do not have a sock lining as such, but they have the equivalent in that the lower edge of the upper merges into and is an integral part of the bottom which directly underlies the foot of the wearer.

A stiff heel counter of the pre-molded type is well known to be desirable because of its ability to lend staunchness and form-retaining qualities to the shoe, and to impart a stylish and attractive appearance to it. The benefits of such a stiff heel counter, coupled with the benefits of a full-length sock lining, are achieved by means of the present invention without encumbering the portion beneath the heel of the wearer with elements or parts which may tend to impair softness and comfort.

The procedural steps by means of which my present invention is carried out are of a simplified character which are easy to perform, expeditious, and inexpensive, requiring no unusual skill on the part of the operator.

In accordance with my present invention, the heel part of the upper, or quarter, is formed of inner and outer plies, joined together along the top and bottom edges and along at least one side, the other side being deliberately left open so that a stiff pre-molded counter can be inserted sideways into the space between the two plies. Prior to the insertion of the counter, the top edge of the quarter is finished in any desired manner, and this may entail the use of an inturned

2

seam, or of a French cording, or the application of ornamentation of various kinds, and whatever the procedure may be it is capable of performance with the parts in relatively flat and soft condition, so that ordinary sewing machines may be employed if desired. It is only as a final step in the manufacturing procedure that the stiff counter is inserted into the pocket and the opening of the pocket sealed to complete the enclosure of the counter within it.

The preferred manner of achieving these general objects and advantages, and such other objects and advantages as may hereinafter appear or be pointed out, is illustratively exemplified in the accompanying drawings in which:

Figure 1 is a perspective view of an illustrative upper;

Figure 2 is a perspective view of a counter-covering element suitable for employment with the upper shown in Figure 1;

Figure 3 is a perspective view showing the initial assembly of the parts shown in Figures 1 and 2;

Figure 4 is a view similar to Figure 3, showing the top edge of the quarter and shoe upper finished by means of an illustrative French cording;

Figure 5 is an enlarged cross-sectional view taken substantially along the line 5—5 of Figure 4;

Figure 6 is a cross-sectional view taken substantially along the line 6—6 of Figure 4;

Figure 7 is a bottom view of the assembly after the sock lining has been attached thereto;

Figure 8 is a fragmentary cross-sectional view taken substantially along the line 8—8 of Figure 7;

Figure 9 is a perspective view of a type of stiff heel counter which may be employed;

Figure 10 is a view similar to Figure 6, showing the heel counter in position;

Figure 11 is a cross-sectional view along the line 11—11 of Figure 10;

Figure 12 is a view similar to Figure 10 showing the counter pocket in completed sealed condition;

Figure 13 is a perspective view of the finished shoe constructed in accordance with the steps indicated in Figures 1—12;

Figure 14 is a view similar to Figure 4, illustrating a modification;

Figure 15 is a perspective view of a modified shoe construction, showing the preliminary assembly of a sock lining and an upper composed of separated vamp and quarter;

Figure 16 is a fragmentary cross-sectional view

taken substantially along the line 16—16 of Figure 15;

Figure 17 is a cross-sectional view taken substantially along the line 17—17 of Figure 15;

Figure 18 is a perspective view of the preliminary assembly of certain parts of the upper in a shoe of modified character;

Figure 19 is a cross-sectional view taken substantially along the line 19—19 of Figure 18;

Figure 20 is a perspective view of the rear end of the finished shoe resulting from the preliminary assembly of parts shown in Figure 18;

Figure 21 is a cross-sectional view taken substantially along the line 21—21 of Figure 20 the lacing being shown in unlaced condition;

Figure 22 is a fragmentary plan view of certain parts of an upper of a shoe of modified construction, shown in a preliminary stage of assembly;

Figure 23 is a perspective view of the upper at a further stage of its construction;

Figure 24 is a cross-sectional view taken substantially along the line 24—24 of Figure 23;

Figure 25 is a cross-sectional view taken substantially along the line 25—25 of Figure 23;

Figure 26 is a view similar to Figure 25 showing the parts associated with the heel counter;

Figure 27 is a cross-sectional view taken substantially along the line 27—27 of Figure 26; and

Figure 28 is a perspective view of the finished shoe formed as indicated in Figures 22—27.

The article of footwear I have chosen to illustrate in Figures 1—13 comprises an upper formed of two parts 30 and 31, joined at the front and back by seams 32 and 33, and associated at the front of the shoe with a plug part 34.

One of the initial steps in the construction of the shoe consists in stitching the counter-covering element 35 of Figure 2 to the upper assembly shown in Figure 1. This association of parts is indicated in Figure 3.

The parts of which the upper is composed, and the element 35, may be of any suitable material, such as leather, fabric, or other substance. The element 35 may assume various shapes. That which is shown in the present drawings provides for a relatively short top edge 36, a relatively long bottom edge 37, and upwardly curving side edges 38 and 39. If desired, a notch may be cut in the element from the mid-portion of the bottom edge, and the edges of the notch stitched together, as indicated at 40, to impart a suitably curved contour to the element 35.

In securing the part 35 to the rear part of the upper assembly shown in Figure 1, stitches 41 extend along the top edge, stitches 42 extend along the bottom edge, and stitches 43 (Fig. 6) extend along one side edge. The opposite side edge is purposely left unattached, as shown most clearly in Figure 6.

The part 35 and the material lying beneath it constitute outer and inner plies of a two-ply quarter. It is one of the features of the invention to finish the top edge of this quarter prior to the insertion of a stiffening counter into the pocket between the two plies. An illustrative finishing of this top edge is indicated in Figures 4 and 5. A French cording 44 extends not only along the top edge of the quarter but also along the top edge of the upper all the way to the plug element 34 (see Fig. 13). The application of such a cording is well known per se, and is most clearly indicated in Figure 5. It involves two stitchings, one which first secures one edge of the cording, wrong side out, to the top edge of the upper,

and a second stitching 46 which secures the other edge of the cording after it has been extended around the edge which it is to cover and ornament.

If desired, the stitches 41 of Figure 3 may be omitted, and the connection of the two plies of the quarter may be effected by the initial row of stitching by means of which the cording 44 is attached. Thus, while I have shown three rows of stitching in Figure 5, it will be understood that the middle row may be omitted, if desired.

A further step in the assembly of the shoe is best indicated in Figures 7 and 8. A full length sock lining 47 is secured along its entire periphery, by means of stitches 48, to the entire lower edge of the upper.

If desired, the stitches 42 of Figure 3 may be omitted, and the joining of the two plies of the quarter along their bottom edges may be achieved by means of the stitches 48.

In the shoe illustrated, the construction also involves a platform wrapper 49 (see Fig. 13). The part or parts which define this wrapper are secured to the other parts either at the same time that the sock lining 47 is stitched into position or thereafter. Thus, it is obvious that the stitches 48 may be employed for the purpose of also securing to the assembly the element or elements 49, or, if desired, a second line of stitches 30 may accomplish this purpose. In any case, since the present invention is not affected by the nature of the sole construction beneath the sock lining 47, the details of the platform, if any, and of the platform wrapper and sole, etc., have not been shown, being well known per se.

The foregoing steps are all performed prior to lasting, and since the parts are relatively soft and can be easily maneuvered into flattened condition, ordinary sewing machines and procedures can be used, and no unusual skill is called for. The sequence of performing the steps thus far described is not important. The characterizing feature of the invention resides in the fact that, while the parts are all in soft unreinforced condition, and prior to the insertion of any stiff reinforcement or counter, the two plies of the quarter are secured together along their top and bottom edges, preferably also along one of the side edges, and are purposely left unattached along the opposite side edge. Also, if the top edge of the quarter is to be finished off or ornamented in some special manner, this is accomplished during the preliminary assembling of the various parts as hereinbefore described.

It is at this stage that a stiff unflanged pre-molded counter 51, substantially of the character shown in Figure 9, is inserted sideways into the space between the two plies of the quarter. After its insertion, as indicated in Figure 10, the open side of the pocket is stitched closed as indicated at 50 in Figure 12. This completes the enclosure of the counter within the pocket.

The assembly is then ready for application to a last (if lasting is desired or needed), and the shoe is then completed in any appropriate and well known manner.

The finished shoe is of the character shown in Figure 13. It has a neat-appearing rigidified heel region and a soft comfortable interior.

The procedure is carried out in exactly the same way, but with a minor modification, in connection with an upper of the kind shown in Figure 14. In this case the counter-covering element 35' is secured to the inside of the upper 52.

As before, it is secured along its top edge, along

its bottom edge, and along one side. The stitches along the side are designated by the numeral 53. The securement along the top edge may be accomplished by a separate line of stitching (not shown) or it may be effected at the same time that the French cording 44' is applied. Similarly, the connection of the element 35' to the upper along the bottom edge may be achieved by a separate line of stitching or it may be accomplished at the time of the attachment to the upper of the sock lining, and by means of the same stitches. It is the deliberate avoidance of securing the edge 54 of the element 35' which provides a pocket which is open at the side and which permits the insertion, sideways into it, of a stiff unflanged pre-molded counter such as that shown in Figure 9. As in the procedure described in connection with Figures 1-13, the insertion of this counter is accomplished only after the various parts of the upper, the sock lining, and the trimming of the top edge of the quarter have been completed. After the counter has been inserted into the pocket, the pocket is stitched closed along the side 54, and the shoe is then ready for completion in accordance with usual procedures.

Figures 15-17 show the applicability of the invention to an article of footwear in which the upper is composed of two separated parts. The forward or vamp part 55 is joined to the rear part or quarter by means of two straps or gores or 30 elastics 56.

In this case, the quarter is composed of inner and outer plies 57 and 58 which are joined together along the top edge by means of an in-turned seam 59 (see Fig. 16). The plies are 35 joined together along their bottom edges by means of stitches 60 (Fig. 16), or, if desired, this securement may be achieved by means of the stitches 61 which secure the lower edge of the upper to the peripheral edge of the sock lining 62.

As before, the sock lining 62 is of full length, and is stitched along its edge to the upper along the entire extent of the lower edge of the upper.

For reasons hereinbefore given, the platform wrapper or wrappers, if the design of the shoe calls for them, have not been indicated in the drawings, but it is during the preliminary assembling of the parts that the platform wrapper is secured in position. It may be held in position by means of the stitches 61, or a separate line of stitching may be employed.

The two plies of the quarter are also preferably stitched together along one side. This is indicated by the stitches 63 in Figure 15. If desired, these stitches may also serve the purpose of securing the rear end of the strap or ribbon 56 in position between the two plies 57 and 58 of the quarter.

The side edges 64 are purposely left disconnected, thus providing a side entrance into the pocket between the plies 57 and 58. After the various parts have been assembled in readiness for application to a last, a stiff counter of the character hereinbefore referred to and shown in Figure 9 is inserted sideways into this pocket, and the open end of the pocket is then sealed by means of stitches 65 (Fig. 17). During the application of the stitches 65, the rear end of the corresponding strap 56 may be engaged and secured to the rear part of the shoe upper.

Obviously, while the counter employed is of the pre-molded unflanged character, its shape will not be exactly like that shown in Figure 9, but will conform more appropriately to the shape of the pocket which is defined by the two plies of 75

the quarter. Such a counter, in the position which it assumes in the finished shoe, is shown at 66 in Figure 17.

The construction shown in Figures 15-17 is 5 illustrative of the applicability of the invention to a shoe in which the upper is composed of separated parts. Obviously, these parts may assume various forms, and may be connected by ornamental means other than the straps 56, or left completely disconnected. Similarly, the top edge of the quarter may be ornamented in a variety of ways, the important feature being that this ornamentation or finishing is accomplished during the initial assembling of the elements and 10 prior to the insertion of the counter.

In Figure 18 a modified upper is shown, in 15 which the counter-covering element 67 is stitched to the elements 68 and 69 along all its edges, prior to the insertion of the counter. 20 This attachment is indicated by the stitches 70 which join the two plies of the quarter along the top edge, by the stitches 71 which join these two plies along the bottom edge, and by the 25 stitches 72 (see also Figs. 19 and 21) along the two sides of the element 67.

As hereinbefore mentioned the stitches 70 along the top may be dispensed with and the connection may be established by any cording or other trimming or ornamentation which is applied to this top edge; and, similarly, the 30 stitches 71 along the bottom may be replaced by the stitches which ultimately join the sock lining 73 (Figs. 20 and 21) to the upper.

The sidewise insertion of the stiff unflanged 35 pre-molded counter (shown at 74 in Fig. 21) is accomplished through the vertical slit 75 which is formed in the counter-covering element 67. This slit may extend only partly to the top and bottom edges of the element 67, as indicated in 40 the present drawings, or it may extend all the way to these edges. In any case, after the parts have been connected along the top and bottom edges, a vertical slit-like opening is provided through which the counter 74 may be maneuvered in a sideward direction, being inserted 45 first into one half of the pocket beneath the element 67, then into the other half.

The final enclosure of the counter 74 within 50 the pocket is achieved by means of lacing 76 which passes through suitable openings formed alongside of the slit 75.

As indicated in Figure 20, this shoe may have 55 a platform cover 77, and other elements forming parts of the outer sole construction. This part of the shoe construction does not play any part in connection with the present invention and the details have therefore been omitted from the drawings. However, the platform wrapper 77, as hereinbefore mentioned, is secured to the upper at the time of the securement of the sock lining 73, or immediately thereafter.

The construction of the parts in the manner 60 shown in Figures 18-21 is particularly useful where the upper elements 68 and 69 are joined together at the rear by means of a seam which projects rearwardly and would normally be unsightly. The element 67 thus fulfills a dual purpose, viz., it covers and conceals this seam or rim, and it also covers and conceals the 65 stiffening counter 74. (For the sake of simplicity of illustration, the parts 68 and 69 have been shown as composed of a single piece of material, but it is obvious that they be joined by a seam 70 of the character referred to, without affecting

the procedure to which the present invention is directed.)

In Figures 22-28 I have shown a further modification of the shoe upper in which the quarter is composed of two plies which are integral parts of a single element doubled upon itself. This element is designated by the reference numeral 78, and is shown in its initially flat condition in Figure 22. When it is doubled upon itself as best shown in Figure 24, it defines inner and outer plies 79 and 80. These plies are obviously joined together along their top edges, since they are parts of a single element, the fold line 81 lying along the top edge. For ornamentation purposes, a line of stitching 82 may be provided along this top edge, to form a bead-like finish which is attractive.

The plies 79 and 80 are joined along their bottom edges by a line of stitches 83, but, as hereinbefore mentioned, this line of stitches may be dispensed and the connection along the bottom edge may be effected by the same stitches which connect the lower edge of the upper to the peripheral edge of the sock lining 84 (Figs. 26-28).

The upper of the shoe, forwardly of the two-quarter, may be composed in part of elements 85 and 86. While I have shown these elements as extending for the full length of the shoe, and joined together at the front, it will be understood that this particular construction is not essential. It will also be understood that any desired plug element, or other suitable vamp construction, may be employed without affecting the procedure to which the present invention is primarily directed.

In assembling the elements, the rear edges of the parts 85 and 86 are first stitched, as at 87 and 88, to the side edges of the inner ply 80. In performing this step, the quarter element 78 is laid flat as indicated in Figure 22, wrong side up, and the parts 85 and 86 are stitched thereto as indicated. The element 78 is then doubled upon itself to define the two plies 79 and 80, and thereupon the assembly is completed in every respect except that one side 89 of the quarter is left disconnected. In the present drawings, I have shown one side of the outer ply 79 disconnected in Figures 23 and 25, but, obviously, if the parts 85 and 86 are first stitched to the outer ply 79 (instead of to the inner ply 80 as shown in Fig. 22), the deliberately disconnected side edge may if desired be formed on the inner ply 80.

During the assembling procedure, the sock lining 84 is secured to the upper, and if a platform wrapper is to enter into the finished construction, as indicated at 90 in Figure 28, it is at this stage of the procedure that it is stitched to the lower edge of the upper. Also, if the upper edge of the quarter is to be finished or ornamented in any way other than the application of the stitches 82, such finishing or ornamentation is accomplished at this time.

It is only then that a stiff unflanged pre-molded counter 91 is inserted sideways into the pocket between the plies 79 and 80, and the pocket sealed by means of the stitches 92. The stitches 93 at the opposite side of the pocket are made during the preliminary assembly hereinbefore mentioned.

The advantages of a quarter composed of a single element doubled upon itself, as shown in Figures 23-28, include the fact that only one cutting of material is necessary, no allowances need to be made for seaming, and the result is neater

and richer looking, devoid of heavy unattractive seams.

In each of the constructions illustrated, I achieved in a simple manner the conjoint advantages of a sock lining which is of full length and which is secured throughout the extent of the lower edge of the upper, the presence of a stiff pre-molded counter in the heel region of the shoe, and a complete absence of any separate tab or heel piece on the inside, covering an unsightly or uncomfortable flange which would normally underlie the heel of the foot, if a flanged counter of ordinary character were employed.

Where the invention is applied to so-called "soft sole" slippers, in which the assembly of the parts, including the inner sole or sock lining, is finished before lasting, the procedure remains the same in respect to the fact that a stiff counter is inserted as one of the final steps before the assembly is applied to a last. After insertion of the counter, the open side through which it was inserted is stitched closed, and the assembly is then applied to the last for completion of the shoe.

The advantages of the invention may be enjoyed in connection with a shoe of the moccasin type by stitching the counter-covering element to the rear part of the upper (either on the outside or on the inside) along the top edge, the bottom edge, and one side edge, leaving the other side purposely disconnected. This provides a pocket which is open at the side and into which the stiff unflanged counter may be inserted in a sidewise direction, the opening of the pocket being thereupon sealed.

Obviously, those skilled in the art may readily make changes in many of the details herein described and illustrated, without necessarily departing from the spirit and scope of the invention as expressed in the appended claim.

Having thus described my invention and illustrated its use, what I claim as new and desire to secure by Letters Patent is:

Those steps in the manufacture of a shoe or slipper having a full-length stitched-in sock lining, a platform sole and wrapper and a counter-stiffened quarter, which comprise: stitching a sock lining along its entire periphery to the lower edge of an upper providing a platform wrapper on said upper, stitching a counter-covering element to the upper but only along its bottom and top edges and along one side so as to form a pocket which is open along the unattached side, inserting a relatively stiff unflanged pre-molded counter sideways into said pocket, then stitching the unattached side of the counter-covering element to the upper to seal said counter within said pocket, and then force lasting the assembly and completing the sole structure of the shoe.

JACK MELTZER.
